[57] CLAIM

The ornamental design for a computer tote bag, as
shown and described.

DESCRIPTION

FIG. 1 is a perspective view of a computer tote bag
showing my new design;

FIG. 2 is a right side elevational view thereof;

FIG. 3 is a bottom plan view thereof;

FIG. 4 is a reduced scale perspective view with the
cover folded back; and

FIG. 5 is a rear elevational view of FIG. 1.
